OUTBOARD MOTOR

David L. Painter, Evanston, Ill.

Application November 30, 1954, Serial No. 33,339

Term of patent 14 years

(Cl. D71—1)

Fig. 2.

Fig. 3.

Fig. 1 is a top plan view of an outboard motor embodying my new design.

Fig. 2 is a rear perspective view thereof, and

Fig. 3 is a front perspective view of the same.

The essential features of my design reside in the portions shown in solid lines.

I claim:

The ornamental design for an outboard motor, as shown and described.
